FIG. 1.

FIG. 2.

FIG. 3.

FIG. 4.

FIG. 1 is a view in side elevation of a passenger vehicle, showing our new design. The opposite side is the same in appearance as the side shown.

FIG. 2 is a top plan view of the passenger vehicle of FIG. 1.

FIG. 3 is a view in front elevation of the passenger vehicle of FIG. 1 removed from the vehicle thereof.

FIG. 4 is a view in rear elevation of the passenger vehicle of FIG. 3.

The dominant features of our design reside in the portions shown in full lines.

We claim:

The ornamental design for a passenger vehicle, as shown and described.
